INVENTOR.

Franklin A. Smith
Jr.

UNITED STATES PATENT OFFICE.

FRANKLIN A. SMITH, JR., OF PROVIDENCE, RHODE ISLAND.

BUTTON-FASTENER.

SPECIFICATION forming part of Letters Patent No. 295,951, dated April 1, 1884.

Application filed January 23, 1884. (No model.)

To all whom it may concern:

Be it known that I, FRANKLIN A. SMITH, JR., a citizen of the United States, residing at Providence, in the county of Providence and State of Rhode Island, have invented certain new and useful Improvements in Button-Fasteners; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My present invention relates to an improved fastener for attaching buttons to fabric, and of that class of cut sheet-metal devices for which I have recently made applications; and my invention consists, essentially, of a fastener 20 cut out of sheet metal of such a form as, when attached to a button in fabric, that the button shall be securely locked in the fastener in such a manner as to render it impossible for the fastener to become detached without bending.

25 To this end my invention consists, practically, of a metal arm, from one edge of which extends a double-curved projection or tongue, both in the same plane, and adapted for use 30 as a button-fastener, as when attached to a button in fabric, as hereinafter described, the fastener will be securely locked therein.

To more clearly illustrate my invention, I refer to the drawings, in which Figure 1 represents my improved fastener ready for use. Fig. 2 represents the fastener after having been locked in a button-eye, but with the button-eye removed; and Fig. 3, the complete device as attached to a button in fabric.

40 Again referring to the drawings, A is a fastener cut out of sheet metal, ready for use without further manipulation, substantially of the form shown in Fig. 1, and it consists of the curved arm a, from the cut edge of 45 which extends the double-curved tongue a', which is of a uniform width its entire length, forming the loop e and elbow d', and terminating in the end d. Between the point c of the arm a and the elbow d' is a space, o, wide 50 enough to permit the passage of a button-eye in attaching it to fabric. The point c of the arm a is angled, as shown, to assist in locking the loop of the fastener when attached to a button. The ends b and d are rounded, to

present a smooth surface to the fabric when 55 attached thereto.

In attaching a button to fabric with my improved fastener, the button-eye is first protruded through the fabric from the outer side. The end d of the tongue is then carried 60 through the button-eye until the loop e rests therein. An upward strain is then brought to bear on the button, which causes the ends b and d of the fastener to be pressed hard 65 against the undersurface of the fabric, and the strain on the button, being continued, causes the points c and d' to approach each other until they meet, forming a closed loop around the button-eye at equal distance between the two ends b and d, as fully shown in Fig. 3. 70 The angled end c, on coming in contact with the elbow d', tends to press it closely against the under surface of the fabric, and the two parts are firmly held together, forming a brace 75 to prevent the ends b and d from straightening out; and it will be observed that the greater the strain on the button-eye the more closely the two parts c and d' are held together, the ends b and d and the end c, with the elbow d', and arm a, forming, when attached to fabric 80 ready for use, a practically one-piece bar with the loop e in the center.

My invention possesses great advantages over other similar devices, in that it is cheaply and easily made, requiring but a single operation to cut the complete fastener ready for use, and combines a great degree of strength and durability, and is not liable to become detached by use.

Having described my invention, what I claim 90 is—

1. The herein-described button-fastener A, consisting of the curved arm a, and double-curved tongue a', arranged and adapted for use substantially as described. 95
2. The herein-described button-fastener A, consisting of the curved arm a, rounded at one end and angled at the other, from the cut edge of which extends the double-curved tongue a', cut to a uniform width its entire 100 length, and adapted for use substantially as shown and described.

In testimony whereof I affix my signature in the presence of two witnesses.

FRANKLIN A. SMITH, JR.
